(57) **CLAIM**

The ornamental design for a phone stand with bluetooth® speaker, as shown and described.

DESCRIPTION

FIG. 1 is a perspective view of a first embodiment of a phone stand with bluetooth® speaker showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof.

FIG. 10 is a perspective view of the phone stand with bluetooth® speaker where the phone stand with bluetooth® speaker is in a configuration of use;

FIG. 11 is a perspective view of the phone stand with bluetooth® speaker where the phone stand with bluetooth® speaker is in a folded state;

FIG. 12 is another perspective view thereof;

FIG. 13 is an enlarged view of portion 13 shown in FIG. 3;

FIG. 14 is a perspective view of a second embodiment of the phone stand with bluetooth® speaker showing my new design;

FIG. 15 is another perspective view thereof;

FIG. 16 is another perspective view thereof;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is a perspective view of the phone stand with bluetooth® speaker where the phone stand with bluetooth® speaker is in a configuration of use;

FIG. 24 is a perspective view of a second embodiment of the phone stand with bluetooth® speaker showing my new design;

FIG. 25 is another perspective view thereof; and,

FIG. 26 is an enlarged view of portion 26 shown in FIG. 16. The broken lines in the drawings depict portions of the phone stand with bluetooth® speaker that form no part of the claimed design.

1 Claim, 26 Drawing Sheets
